(57) **CLAIM**

The ornamental design for a power adapter, as shown and described.

DESCRIPTION

FIG. 1 is a top, front perspective view of a power adapter, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the power adapter. In the drawings, the broken lines are for the purpose of illustrating portions of the power adapter that form no part of the claimed design.
